(57) **CLAIM**

The ornamental design for a cooling pipe for automotive battery as shown and described.

DESCRIPTION

FIG. 1 is a perspective view of a cooling pipe for automotive battery, showing my new design;

FIG. 2 is a front elevation view thereof;

FIG. 3 is a rear elevation view of thereof;

FIG. 4 is a left side elevation view thereof;

FIG. 5 is a right side elevation view thereof;

FIG. 6 is a top plan view thereof; and,

FIG. 7 is bottom plan view thereof.
